UNITED STATES PATENT OFFICE

ADALBERT BELA FELDMAR, OF BERLIN-SCHONEBERG, GERMANY

STONE DRILL

Application filed January 23, 1925. Serial No. 4,337.

The present invention relates to a drill for producing holes in stone and stone-like materials of all kinds, said drill being of the type which require to be manipulated by a series of blows. The drill is driven into the stone or similar material by means of a hammer, at the same time being rotated by hand or by means of a suitable holder.

Some of the stone drills of this type hitherto known possess the disadvantage that when being used they are liable to become wedged in the boring being produced, and can then only be rotated with difficulty. The object of the present invention is to over-
come this said defect.

According to the invention the cutting edge of the drill is curved outwardly at the leading sides, i. e., at the rear part of each leading side proceeding along the edge of the grooves in the shaft. This outward curve of the cutting edge results in the drill after having been driven in to a certain extent automatically releasing itself, becoming loose, and therefore easily capable of being rotated. The effect of this embodiment of the leading sides is still further increased if the trailing sides are ground slightly concave.

A form of embodiment of the invention is described by way of example in the following, reference being made to the accompanying drawing.

Fig. 1 is a front elevational view of the drill.

Fig. 2 is an enlarged detail showing the cutting edge.

Fig. 3 is a top plan view of the drill.

Figs. 4, 5 and 6 are sections on lines IV-IV, V-V, VI-VI.

The invention is described in connection with a drill 1 having a holder 2, a chisel-like, curved cutting edge 3, and two grooves 4 in the shaft. The chisel-like cutting edge 3 possesses two alternately disposed leading sides 5 and two trailing sides 6.

The invention consists in providing the leading sides at the rear part with an outwardly curved elevation 8 running along the edge 7 of the grooves 4. This outwardly curved elevation 8 extends gradually from the

outside beyond the centre of the cutting edge 3. If the drill is driven in by means of a hammer the cutting edge 3 at first acts in the usual manner. When, however, the outwardly curved elevation 8 of the cutting edge 55 comes into contact with the stone or wall, this causes the drill to recoil, the latter thus automatically being released or loosened, so that same may be rotated without difficulty, the leading sides 5 operating in the usual 60 manner.

The effect of this embodiment of the leading parts 5, 8 is further increased if the trailing parts 6 are ground somewhat concave. Such an inward curvature moreover pos- 65 sses the advantage that the material removed from the boring is able to pass without hindrance into the grooves 4.

What I claim is:

1. A stone drill, comprising a cylindrical 70 body portion, a curved chisel-like cutting edge at one end of the body portion with leading and trailing sides, oppositely disposed grooves in the body portion, the leading sides to the cutting edge being bordered 75 adjacent the grooves with a convex portion, making a slightly greater angle with respect to the axis of said body portion, than the respective sides of said cutting edge, there being no plane with respect to which the 80 leading and trailing sides are symmetrical.

2. A stone drill comprising a cylindrical body portion, a curved chisel-like cutting edge at one end of the body portion, oppositely disposed grooves in the body portion, convex leading sides to the cutting edge 85 and concave trailing sides to the cutting edge, the leading and trailing sides being unsymmetrical relative to planes including the longitudinal axis of the body portion. 90

3. A stone drill, comprising a cylindrical body portion, a curved chisel-like cutting edge at one end of the body portion with leading and trailing sides, oppositely disposed grooves in the body portion, the leading sides to the cutting edge being bordered adjacent the grooves with a convex portion making a slightly greater angle with respect to the axis of said body portion than the respective sides of said cutting edge, there 100

being no plane with respect to which the leading and trailing sides are symmetrical, the trailing sides being concave.

In testimony whereof I have affixed my signature.

ADALBERT BELA FELDMAR.
